[57]**CLAIM**

The ornamental design for a strap connector for wristwatch, as shown and described.

DESCRIPTION

FIG. 1 is a top plan view of a strap connector for wristwatch showing my new design;
FIG. 2 is a left side elevational view;
FIG. 3 is a right side elevational view;
FIG. 4 is a front elevational view;
FIG. 5 is a bottom plan view;
FIG. 6 is a rear elevational view;
FIG. 7 is a top plan view of a second embodiment of my new design of FIGS. 1-6;
FIG. 8 is a left side elevational view;
FIG. 9 is a right side elevational view;
FIG. 10 is a front elevational view;
FIG. 11 is a bottom plan view; and
FIG. 12 is a rear elevational view thereof.

The broken line showing of a watch case and wrist strap are environmental only and form no part of the claimed design.
